UNITED STATES PATENT OFFICE

JESSE G. KING, OF DAYTON, OHIO, ASSIGNOR, BY MESNE ASSIGNMENTS, TO FRIGID-AIRE CORPORATION, A CORPORATION OF DELAWARE

REFRIGERATING APPARATUS

Application filed October 27, 1927. Serial No. 229,243.

This invention relates to improvements in refrigerating apparatus and more particularly the refrigerating elements or cooling units used in mechanical refrigerators.

It is among the objects of the present invention to provide an improved cooling unit having relatively wide heat absorbing surfaces and arrange for relatively uniform and effective heat transfer relationship between the parts of the heat absorbing surfaces and the circulating medium to be cooled thereby. In carrying out the above object, I provide relatively elongated metal fins in the form of wings and I insure cooling of the entire wing by conveying refrigerant to remote parts thereof. In a preferred arrangement, I provide a header for liquid refrigerant and extend elongated fins from the header in a lateral direction to form wing type fins and convey refrigerant from the header to at least midway to the tips of the wings whereby the temperature gradient between the parts of the wings adjacent the header and the parts adjacent the tips of the wing is reduced and in this manner I establish a more nearly uniform and effective temperature difference between all of the parts of the cooling unit and the circulating medium to be cooled.

It is another object of the invention to provide an improved cooling unit suitable for use in refrigerators where more width than height is available for positioning the cooling unit.

Further objects and advantages of the present invention will be apparent from the following description, reference being had to the accompanying drawing, wherein a preferred form of the present invention is clearly shown.

In the drawings

Fig. 1 represents a top view of the improved refrigerating element of the invention;

Fig. 2 is a side view of the same;

Fig. 3 shows a cross section of a portion of the element taken on the line 3-3 of Fig. 2, and

Fig. 4 illustrates a refrigerator equipped with the refrigerating element of the inven-

tion and provided with means for securing an efficient circulation of cold air.

Referring in detail to the drawings, the refrigerating element or cooling unit comprises a header or tank 10 which serves as a container for holding a refrigerating medium which may for example be liquid sulphur dioxide. This tank serves to distribute the refrigerant to pipes or ducts hereinafter described. The refrigerating medium is led into the header tank by means of a pipe 11 and is led off therefrom above the liquid level in the tank by means of a pipe 12, a suitable float valve, not shown, being used to maintain a constant level of liquid in the tank. One of the features of the invention comprises a series of cooling ducts which are formed of a plurality of dependent ducts or loops of pipes, all of which are connected to the header in parallel circuit relation as shown in the drawings in Fig. 2. These ducts extend downwardly into the air cooled by the refrigerating element, and are hereinafter referred to as loop sets 13-14 each set including a loop 13 and a loop 14. The loops or ducts constituting a set are constructed substantially as follows: The loop 13 has a vertical duct or leg 13', Fig. 2, depending substantially adjacent the vertical axis of the header 10 and a second vertical duct or leg 13'' which is offset laterally a considerable distance from the same axis and which also depends from the header.

The loop 14 of the loop set also has a vertical leg 14' depending downwardly substantially adjacent the vertical axis of the header 10 but on the opposite side of the header as regards leg 13'. The second vertical leg 14'' of this loop depends downwardly laterally offset to a considerable extent, similar to leg 13''. Thus legs 13'', 14'', and 13', 14', may be said to be similarly positioned although belonging to separate loops.

It will be observed that all of the loops marked 13 and 14 are built up in the same shape but when they are attached to the header 10, alternate loops are turned reversely so that the laterally offset legs 13'', 14'' project alternately on opposite sides of the header. The vertically depending legs 100

13', 13'' are connected with each other at the bottom by means of cross legs or ducts 13''' and at the top by similar cross ducts or legs 13''' of shorter length than the bottom cross ducts. The same is true of the loops 14 which have their vertical legs 14' and 14'' connected by similar cross ducts at the top and bottom 14''', the top cross legs being shorter than the bottom ones.

10 The loop sets 13-14 each have a copper fin 15 attached, as by soldering to insure good thermal contact. These fins preferably lie in substantially the same plane as both loops 13-14 and the fin is attached to 15 one side of one loop on one side of the fin and to the other side of the other loop on the other side of the fin as shown in Fig. 3. These fins extend from the header and are elongated in a lateral direction to form, what 20 may be termed, wing type fins providing wide heat absorbing surfaces lying preferably in the direction of circulating air or medium flowing thereover. The fins may have their edges bent over as at 16 to 25 strengthen them and prevent damage.

Inasmuch as the refrigerating element is adapted to be used as a substitute for a relatively flat cake of ice or adapted to be used in refrigerators where space is available 30 which is wider than it is high, the vertically depending legs 13', 14' which are substantially adjacent the vertical axis of the header are relatively shorter than the cross ducts 13''', 14''' which connect them with the most laterally extending legs 13'', 14''. The fins should also preferably extend horizontally in the same direction and preferably beyond the most laterally located legs. The header is arranged to straddle the loop-fin structure 40 as shown in Fig. 2.

An important feature of the present invention lies in establishing a more nearly uniform and effective temperature difference between all parts of the wing type fins and the 45 medium to be cooled. In the specific embodiment illustrated, I reduce the temperature gradient between remote parts of the fin wings and the parts adjacent the header by extending the refrigerant conveying ducts 50 outwardly from the header to at least midway to the tips of the wings. In this manner the parts of the wings remote from the header are effectively cooled and a more nearly uniform and effective temperature 55 difference is established between all parts of fin wings and the circulating medium or air to be cooled.

It is evident that the structure above described furnishes a refrigerating element of 60 great width as compared to its height and that the fins produce passageways which aid in circulating and guiding the refrigerated air. The extreme length or width of the element compared with its height permits 65 the air to creep along in a horizontal direc-

tion for a relatively long distance and the element is therefore well adapted for use in refrigerators whose flues are considerably separated and where it is desired to avoid the use of a plurality of smaller and more 70 compact units. A feature of the invention therefore resides in the straddling of the header over a finned loop system having great width compared to its length.

Fig. 4 shows the improved refrigerating element mounted in a refrigerator cabinet. The refrigerator comprises a cabinet having an exterior wall 17 and an impervious interior lining 18, the space 19 between the two being filled with cork board or similar insulating material. The refrigerator is provided with a chilling chamber, preferably located in the top-most portion of the cabinet and a food compartment 28. The chilling chamber comprises a bottom wall 20 of insulating material and baffle side walls 21. These walls are attached to the front and rear walls (not shown) of the cabinet. A flue 22 is provided in the bottom wall of the floor of the ceiling compartment and this may be equipped with a ventilating hood 23, which will permit cold air to enter the compartment below but will prevent water from dripping into the compartment when the refrigerating element is defrosted. The baffle side walls of the chamber do not extend to the top of the cabinet but are arranged so as to provide openings 24 which communicate with flues 25 leading to the lower portion of the cabinet.

The refrigerating element of the invention is mounted in the chilling chamber in any suitable manner such as by means of hanger members 26 attached to the header and the roof of the chilling chamber. Shelves 27 are provided in the cabinet and may be of any suitable type, either of screening or built solid and spaced away from the walls so as to permit unhindered circulation of air within the cabinet. Sectional shelves diagrammatically shown in the drawings may also be used, a central passageway through the vertical center being provided for the circulation of air.

In the operation of the refrigerator cold air coming from the chilling compartment passes downwardly through flues 22 in the floor of the chilling chamber. The air, after cooling the contents of the refrigerator, ascends and is forced back to the cooling unit through flues 25 located between the baffle side walls of the chilling chamber and the inside walls of the cabinet. The contents of the cabinet are therefore effectively cooled, the air circulation being approximately 115 shown by arrows in Fig. 4.

It is quite apparent from the foregoing that the air entering the cooling unit section is progressively cooled. Therefore, the parts of the fins adjacent the tips will be 120

somewhat warmer than the parts adjacent to the header and, of course, the legs 13" and 14" will be subjected to a higher temperature than the respective opposed legs 13' and 14' of the loops. This arrangement causes a thermally non-symmetrical relation of the branches of the loops and therefore a thermally non-symmetrical relation of the loops with respect to the plane of the vertical axis of the header and the refrigerant will boil more violently in legs 13" and 14" than in legs 13' and 14'. Consequently, more gas and less liquid will be present in the former legs than in the latter. This difference of apparent density of refrigerant in the vertical parts of the opposed legs or branches will create unbalanced columns of refrigerant to cause, what may be termed, a prevalent flow of refrigerant downwardly from the header, through the branches 13' and 14', through the cross legs 13''' and 14''', whence the refrigerant gas will flow upwardly through the opposed vertical branches to the header. By establishing a prevalent flow, as above described, in contradistinction to a circuit in which the liquid flows in one direction and vapor in the opposite direction, the upward flow of vaporized refrigerant in one of the opposed branches in which the vaporization is greater, the gaseous refrigerant can escape more readily because its upward movement is not impeded by the movement of the downwardly flowing liquid refrigerant. Thus by my arrangement, I provide a circuit in which the vaporized refrigerant readily flows therefrom and is immediately replaced by liquid refrigerant to thus improve the thermal efficiency of the circuit.

In view of the width of the refrigerating element as compared to its height it is apparent that the same is applicable to refrigerators where but little ice space is available, such as those adapted for holding a flat cake of ice. The far-reaching horizontal spread of the refrigerating element makes it applicable also to cabinets in which the air flues are considerably separated, thus obviating the necessity of using a plurality of individual elements. The efficiency of the element and therefore of the refrigerator as a whole is greater than when ice is employed, since the cooling effect of ice is merely a function of the surface area thereof lapped by the circulating air. The finned-loops present parallel air passageways which in addition to having a far greater total than is presented by the surface of a block of ice, promote a very efficient circulation of air.

While the form of embodiment of the invention as herein disclosed, constitutes a preferred form, it is to be understood that other forms might be adopted, all coming within the scope of the claims which follow.

What is claimed is as follows:

1. A refrigerating element for mechanical refrigerators comprising a header, a series of duct loops depending from said header and connected thereto in parallel, said loops each having a leg depending vertically from one side of said header and adjacent the vertical axis thereof and another leg on the other side of said header but offset laterally to a great extent from said vertical axis, alternate loops being turned reversely with respect to each other, the legs of each loop being connected by cross ducts of greater length than said vertical legs, a fin in a plane formed by one side of one loop on one side of said header and the other side of a corresponding loop on the other side of said header, said header being arranged transversely of the loops and fins. 70

2. A refrigerating element for mechanical refrigerators comprising a header, a series of duct loops depending from said header and connected thereto in parallel, said loops each having a leg depending vertically from one side of said header and adjacent the vertical axis thereof and another leg on the other side of said header but offset laterally to a great extent from said vertical axis, alternate loops being turned reversely with respect to each other, the legs of each loop being connected by cross ducts of greater length than said vertical legs, a fin in a plane formed by one side of one loop on one side of said header and the other side of a corresponding loop on the other side of said header. 80

3. A refrigerating element for mechanical refrigerators comprising a plurality of duct loops having a common inlet and each having a plurality of downwardly extending legs and a connecting leg of greater length than the vertical legs, said loops being arranged in staggered relation to provide at least three parallel rows of legs, and a fin arranged parallel with the loops and having one surface thereof thermally connected with one of said loops and having its opposite surface thermally connected with another of said loops. 90

4. A refrigerating element for mechanical refrigerators comprising a header, a plurality of ducts depending from said header and arranged in at least three substantially evenly spaced parallel rows, a fin arranged transversely to said rows and having one surface thereof thermally connected with one of said ducts and having its opposite surface thermally connected with another of said ducts. 100

5. A refrigerating element for mechanical refrigerators comprising a header, a plurality of ducts depending from said header and arranged in at least three substantially evenly spaced parallel rows, a fin arranged transversely to and spanning said rows, said fin having one surface thereof thermally con- 110

nected with one of said ducts and having its opposite surface thermally connected with another of said ducts.

6. A cooling unit for a refrigerator comprising, a header, fins extending from said header and elongated in a lateral direction to form wing type fins, and means for reducing the temperature gradient between the parts of the wing adjacent the tip thereof and those adjacent the header to establish a more nearly uniform and effective temperature difference between the fin wing and the medium to be cooled thereby, said means comprising refrigerant ducts connected with the header and extending a substantial distance laterally outward therefrom to a region of the wing at least midway to the tip of the wing.

7. A cooling unit for a refrigerator comprising, an elongated header, fins extending transversely of the header and elongated to form wing type fins, said wing type fins being spaced from one another rearwardly substantially coextensive along the length of the header, and means for reducing the temperature gradient between the parts of the wing adjacent the tip thereof and those adjacent the header to establish a more nearly uniform and effective temperature difference between the fin wing and the medium to be cooled thereby, said means comprising refrigerant ducts connected with the header and extending a substantial distance laterally outward therefrom to a region of the wing at least midway to the tip of the wing.

8. A cooling unit for a refrigerator comprising, a header, fins extending from said header and elongated in a lateral direction to form wing type fins, and means for reducing the temperature gradient between the parts of the wing to establish a more nearly uniform and effective temperature difference between the fin wing and the medium to be cooled thereby, said means comprising at least three refrigerant ducts connected with the header and spaced substantially even distances laterally from one another.

9. A cooling unit for a refrigerator comprising, a header, fins extending from said header and elongated in a lateral direction to form wing type fins, and means for reducing the temperature gradient between the parts of the wing to establish a more nearly uniform and effective temperature difference between the fin wing and the medium to be cooled thereby, said means comprising at least three refrigerant ducts connected with the header and spaced substantially even distances laterally from one another and from the tips of the wings.

10. A cooling unit for a refrigerator comprising, a header, fins extending from said header and elongated in a lateral direction to form wing type fins, and means for reducing the temperature gradient between the parts thereof to establish a more nearly uni-

form and effective temperature difference between the fin wing and the medium to be cooled thereby, said means comprising refrigerant ducts connected with the header and thermally connected with the wings relatively near the vertical axis of the header, and refrigerant ducts connected with the header and extending a substantial distance laterally outward therefrom and thermally connected to a region of the wings at least midway to the tips of the wings.

11. A cooling unit for a refrigerator comprising, a header, fins extending from said header and elongated in a lateral direction to form wing type fins, and means for reducing the temperature gradient between the parts thereof to establish a more nearly uniform and effective temperature difference between the fin wing and the medium to be cooled thereby, said means comprising refrigerant duct loops connected with the header, said loops each having a loop leg thermally connected with a wing relatively near the vertical axis of the header, and having a loop leg extending a substantial distance laterally outward from the header and thermally connected to a region of a wing at least midway to the tip of the wing.

12. A cooling unit for a refrigerator comprising, a plurality of duct loops, a substantially centrally disposed header, said duct loops including a downwardly extending leg arranged relatively near the vertical axis of the header and including a downwardly extending leg relatively more remote from the vertical axis of the header, and fin means bridging and thermally connected with one of said first mentioned and one of said second mentioned legs.

13. A cooling unit for a refrigerator comprising, a plurality of duct loops, a substantially centrally disposed header, said duct loops including a downwardly extending leg arranged relatively near the vertical axis of the header and including a downwardly extending leg relatively more remote from the vertical axis of the header, and fin means extending outwardly a substantial distance beyond one of said legs and also bridging and thermally connected with one of said first mentioned and one of said second mentioned legs.

14. A cooling unit adapted to be placed in the path of a cooling medium flowing thereover, said cooling unit comprising a header, duct means connected with the header providing a refrigerant circuit having its ends connected with the header, fin means connected with substantially opposed branches of the circuit, said fin means and branches being arranged for causing one of said opposed branches of the circuit to be subjected to a larger heat exchange area than the other of said opposed branches.

15. A cooling unit adapted to be placed in

- the path of a cooling medium flowing thereover, said cooling unit comprising a header, duct means connected with the header, providing a loop having its ends connected with the header, fin means connected with substantially opposed branches of the loop, said fin means and branches being arranged for causing one of said opposed branches of the loop to be subjected to a larger heat exchange area than the other of said opposed branches.
16. A cooling unit adapted to be placed in the path of a cooling medium flowing thereover, said cooling unit comprising a header, duct means connected with the header providing a refrigerant circuit having its ends connected with the header, one branch of said circuit being disposed relatively near the vertical axis of the header and another branch of said circuit being disposed relatively more remote from said axis of the header, and a fin thermally connected with both of said branches.
17. A cooling unit adapted to be placed in the path of a cooling medium flowing thereover, said cooling unit comprising a header, duct means connected with the header, providing a loop having its ends connected with the header, one branch of said loop being disposed relatively near the vertical axis of the header and another branch of said loop being disposed relatively more remote from said axis of the header, and a fin thermally connected with both of said branches.
18. A cooling unit adapted to be placed in the path of cooling medium flowing thereover for cooling such medium, said cooling unit comprising a header, duct means connected with the header, said duct means providing a refrigerant circuit having its ends connected with the header, and fin means thermally connected with opposed branches of the circuit, said fin means and duct means cooperating to provide a thermally non-symmetrical relation of the circuit with respect to the plane of the vertical axis of the header.
19. A cooling unit adapted to be placed in the path of cooling medium flowing thereover for cooling such medium, said cooling medium flowing thereover, said cooling unit comprising a header, duct means connected with the header, said duct means providing a loop having the ends thereof connected with the header, and fin means connected with substantially opposed branches of the loop, said fin means and loop cooperating to provide a thermally non-symmetrical relation of the loop with respect to the plane of the vertical axis of the header.
20. A cooling unit adapted to be placed in the path of cooling medium flowing thereover for cooling such medium, said cooling unit comprising a header, duct means connected with the header, said duct means providing a refrigerant circuit having its ends connected with the header, and fin means thermally connected with opposed branches of the circuit, said fin means and duct means cooperating to provide a thermally non-symmetrical relation of the circuit with respect to the plane of the vertical axis of the header.
21. A cooling unit adapted to be placed in the path of cooling medium flowing thereover, said cooling unit comprising a header, duct means connected with the header, said duct means providing a loop having the ends thereof connected with the header, and fin means thermally connected with opposed branches of said loop, said fin means and loop cooperating to provide a thermally non-symmetrical relation of the opposed branches of the circuit.
22. A cooling unit adapted to be placed in the path of a cooling medium flowing thereover, said cooling unit comprising a header, duct means connected with the header providing a refrigerant circuit having its ends connected with the header, and fin means thermally connected with opposed branches of the circuit, said fin means and circuit being arranged for causing the refrigerant in one of the said branches to have a different apparent density than the other of said opposed branches.
23. A cooling unit adapted to be placed in the path of cooling medium flowing thereover, said cooling unit comprising a header, duct means connected with the header providing a loop having the ends thereof connected with the header, and fin means thermally connected with opposed branches of the loop, said fin means and loop being arranged for causing the refrigerant in one of said opposed branches to have a different apparent density than the other of said opposed branches.
- In testimony whereof I hereto affix my signature.
- JESSE G. KING.
